BALLAST FOR GASEOUS DISCHARGE DEVICES

Leopold Mauerer, Chicago, Ill., assignor to Jefferson Electric Company, Bellwood, Ill., a corporation of Illinois

Application August 27, 1948, Serial No. 46,407

7 Claims. (Cl. 171—119)

1.

This invention relates to an improved ballast for gaseous discharge devices.

The type of ballast to which this invention is primarily directed is a two-lamp ballast having three separate windings arranged on a common core. The middle winding constitutes the primary and secondary coils of a transformer, and the end windings constitute reactors, one reactor being provided for each of the gaseous discharge devices. The transformer may be either of the insulated or of the autotransformer type, and each of the circuits, including one of the reactors, and one of the gaseous discharge tubes, are connected in parallel with each other across the secondary of the transformer. In other words, the transformer provides a secondary coil which is common to both of the secondary circuits.

It is an object of my invention to provide a ballast of this type which is characterized by low manufacturing costs, improved efficiency, and silence of operation. More specifically, I provide a core structure which is formed from two identical stampings, both of which are comparatively long with respect to their width. Core laminations are stamped from strip stock which is advanced toward the die. By providing a lamination shape of comparatively small width, the rate of stamping is considerably increased since the step by step movement of the strip is comparatively small.

Manufacturing cost is further reduced by the fact that there is very small waste of stock in stamping out the laminations. Furthermore, since the core structure is built up from only two stacks of laminations which are assembled merely by abutting them together, the assembly difficulties in certain prior art ballasts which require three or more stacks to be maintained in alignment are obviated.

It has further been found that there is greater reluctance and greater core losses when the flux runs across the grain of the lamination material than when it runs parallel to the grain. A further object of this invention is to provide a ballast in which the windings and the core are so arranged that the major portion of the flux path of each winding is disposed parallel to the grain of the lamination material, thereby reducing the reluctance and the iron losses.

A still further object is to provide a ballast in which air gaps are provided in the winding legs of the reactor coils, and in which the air gap is completely surrounded by the reactor coil. Thus, an arrangement is produced which reduces the leakage flux which goes through the case with

2.

the result that hum due to vibration of the wall of the casing is substantially eliminated. Iron losses in the case are also reduced by this arrangement.

Furthermore, in the present arrangement, the width of the air gaps is determined by the die which stamps out the laminations. Thus, more uniform electrical characteristics can be obtained, than when each transformer is individually gapped on test.

Still another object is to provide a ballast in which the transformer and reactor windings are arranged on parallel axes, thereby permitting the use of more efficient coil proportions. One type of fluorescent lamp fixture now in common use calls for a long and narrow ballast. The usual prior art ballast of this type has the coils arranged coaxially, and this results in a long coil of comparatively small diameter and in which the cross section of the coil and the window required thereby has a length to width ratio of as great as six to one. The present invention permits the use of coils having a coil cross section ratio of as little as three to one which reduces the intra coil leakage to a minimum as contrasted with the longer and narrower coils of the prior art ballasts.

A still further object is to provide a ballast which is less subject to over-heating. Due to the fact that the core is formed from only two stacks, each of which partially link three separate windings, there is less danger of localized over-heating due to a heavy current carried by one coil. This is for the reason that the core will serve to conduct the heat away from one coil and distribute it uniformly throughout the whole core, which is not the case when a separate core stack is used for each winding.

Other objects, features and advantages will become apparent as the description proceeds.

With reference now to the drawings in which like reference numerals designated like parts:

Fig. 1 is a top view of a ballast made in accordance with my invention, the casing being removed;

Fig. 2 is an elevation of the ballast of Fig. 1, and also showing the casing in section;

Fig. 3 is a section taken along line 3—3 of Fig. 2 and which also shows the casing in section;

Fig. 4 is an elevation of a single lamination;

Fig. 5 is a diagrammatic representation of a lighting system embodying my invention, and

Fig. 6 is a section taken along line 6—6 of Fig. 3.

The ballast is designated generally by the reference numeral 10 and includes a casing 11 and a core 12 which is disposed within the casing. The core has a middle winding leg 13 and two outer

winding legs 14, 15 which are parallel to the middle winding leg. A transformer winding 16 is disposed on the middle winding leg. The transformer winding may be of the insulated type or of the autotransformer type. As shown in Fig. 5 the transformer winding comprises a secondary coil 17 and a primary coil 18 which are connected together in autotransformer relationship.

On the outer winding legs 14 and 15 are mounted reactor windings 20 and 21 respectively, these being connected in series with the secondary coil 17 as shown in Fig. 5. A condenser 19 is connected in series with reactor winding 21, and a gaseous discharge tube 25 is connected in series with the reactor 21 and condenser 19 by means of conductor 23. Similarly, a conductor 22 connects the tube 24 in series with reactor 20. A common conductor 26 connects the opposite ends of the tubes 24 and 25 to the primary coil 18. Primary leads 27 and 28 supply power to the primary.

As shown in Figs. 1 and 3, the core 12 comprises two lamination stacks 30 and 31, each of which are formed from a plurality of identical laminations 32, one of which is shown in Fig. 4. The lamination is an elongate member stamped from suitable steel stock in which the direction of the grain runs across the shorter dimension, as shown by the arrow 33. Lamination material comes in long strips, the grain direction of which runs the length of the strips. Thus, in stamping the laminations 32, stock is advanced with respect to the die at each stamping operation, only by a distance which substantially equals the width of the lamination strip 32. Thus, stamping may be effected at much more rapid rate than in the case of other types of laminations which are now on the market.

One of the longitudinal edges of the lamination strips may be considered as the abutting edge 34, since this is the edge which abuts the corresponding edge of an oppositely disposed strip. Three pairs of slots extend inwardly from the abutting edge 34. Slots 35 and 36 define a tongue portion 14a which constitutes one-half of the winding leg 14. Slots 37 and 38 define a tongue portion 13a which constitutes a portion of the winding leg 13. Slots 39 and 40 define a tongue portion 15a which constitutes a portion of the winding leg 15. The remaining tongue portions are indicated by the reference numerals 41-44 inclusive and constitute yoke portions, since they provide return paths for the flux which is produced by the various coils which are positioned on the winding legs.

The tongue portions 14a and 15a are somewhat shorter than the remaining tongue portions so that when two laminations are arranged in the intended abutting relationship, air gaps 46 and 47 will be provided in the outer winding legs 14 and 15 respectively. Since the width of this gap is determined by the lengths of the tongues 14a and 15a, the width will be uniform, not only for all pairs of lamination in a given core but also for all cores in a given production run. Thus, uniform electrical characteristics are provided.

Since the gaps 46 and 47 are disposed within the coil, any fringing or stray flux which occurs due to the presence of the gap will not effect the transformer casing 11 which is formed from magnetic material. Thus, casing hum is eliminated.

The air gaps 46 and 47 may be filled with gapping material if desired, but I have found that there is no appreciable hum even when the gaps are not filled. This is believed to be due to the fact that that portion of the length of each stack

which is subject to flexing is comparatively small with respect to that portion which is subtended by abutting tongue portions, and hence not subject to flexing.

However, if gapping material is used, the present arrangement lends itself ideally to the use of a cement for the gapping material. For instance, an amount of cement can be placed on the edge surfaces of the outer winding legs 14 and 15 which amount is slightly in excess of that required. In the process of abutting the lamination stacks, the excess cement is squeezed laterally out of the gaps 46 and 47 with the result that the gap is completely filled. Since the gap 15 is surrounded on all sides by the coil spool, the cement which is a semi-conductor when wet will not damage or affect any current carrying parts.

The laminations may be formed so as to provide the proper spacing between the three separate windings. As shown in the drawings, there is a greater spacing between the windings 20 and 16 than between the windings 21 and 18.

As shown in Fig. 4, the corners of the lamination 32 are clipped off as indicated by the reference numeral 50, and notches 51 are formed opposite tongue portions 14a, 42, 13a and 15a. These notches provide a space for the compound (not shown) to work its way into the comparatively small space between the core and the casting. The stamping of these notches in the edge opposite the longitudinal abutting edge 34 is also believed to distribute any internal strain which results from the stamping of the slots 35 to 40 inclusive. Thus, any tendency of the lamination to warp or bend is overcome.

The lamination stacks 30 and 31 may be secured to each other by any suitable clamping means. As shown in the figures, I prefer to use 40 clips 52 which serve to connect the abutting tongue portions 41-44 inclusive. These clips are of the type disclosed in my Patent No. 2,378,233, issued June 12, 1945. As shown in Fig. 1, the clips are secured to the lamination stack 31 by means of rivets 53, and a tongue portion 54 of each clip 52 engages a headed pin 55 which passes through lamination stack 32. When the tongue portions are brought into final position the two lamination stacks will be drawn into tightly 50 abutting relationship.

During operating conditions, that is, when the tubes 24 and 25 are illuminated, the current in the tube circuit 25 will be leading and the current in the tube circuit 24 will be lagging. The 55 values of the condenser 19 and reactor winding 21 are such that there is a preponderance of capacitive reactance during operating conditions, and this preponderance of capacitive reactance substantially offsets the inductive reactance provided by the reactor winding 20. Thus, the power factor of the supply current is substantially unity during normal operating conditions. This is standard practice, and by the term "power factor of substantially unity" is meant anything between 85% and 100% either leading or lagging, since the standard practice varies within these limits.

Under open circuit conditions, when no current 70 is flowing, there will be substantially no voltage drop across the reactors 20 and 21 and across the condenser 19 with the result that the full voltage of the transformer winding 16 will be applied across the tubes. As soon as the tube ignites, 75 however, the desired ballasting action is provided

by the aforementioned elements with the result that the desired operating voltage is obtained.

The usual starting circuits are provided for the tubes 24 and 25, these circuits being indicated generally by the reference numerals 56 and 57 respectively. The starting circuit 56 for the lag tube includes starter 58, and the circuit 57 for the lead tube includes starter 59 and a compensating coil 60. The coil 60 may be incorporated with the reactor winding 21 with the result that it does not appear as a separate coil in Figs. 1 to 3 inclusive.

If desired, the ballast herein shown and described may be used in two-lamp circuits other than that shown in Fig. 5. For instance, an additional condenser may be provided so that both tube circuits are leading.

Irrespective of the particular type of circuit, I have found that the core arrangement of my invention provides a ballast of improved and uniform electrical characteristics as well as a ballast that is easy to assemble, and that costs less to manufacture.

For instance, the parallel disposition of the windings permits the use of more efficient coil proportions. Furthermore, the heat developed in one portion of a lamination stack under heavy load conditions will be immediately conducted to other portions of that stack which are remote from the particular winding which is affected by the heavy current drawn. Thus localized overheating is eliminated.

I claim:

1. A ballast for two fluorescent lamps comprising a core having a middle winding leg, two outer winding legs the axes of which are spaced from the axis of said middle winding leg and are disposed parallel thereto, and four yoke portions the axes of which are parallel to the axes of said winding legs, two of which yoke portions are disposed between adjacent winding legs, and two of which are disposed exteriorly of said outer winding legs, a transformer winding disposed on said middle winding leg, two reactor windings, each being disposed on one of said outer winding legs, and a casing of magnetic material enclosing said core and said windings.

2. A ballast as claimed in claim 1 in which said core is formed from two abutting lamination stacks formed from identical laminations.

3. A ballast as claimed in claim 2 in which each lamination comprises an elongate strip having a longitudinal abutting edge, and in which the grain of the stock from which the lamination is formed runs perpendicular to said longitudinal abutting edge.

4. A ballast for two fluorescent lamps comprising a core having a middle winding leg, two outer winding legs spaced from and disposed parallel thereto, and four yoke portions, two of which are disposed exteriorly of said outer winding legs and two of which are disposed between adjacent winding legs, a transformer winding disposed on

said middle winding leg, two reactor windings, each being disposed on one of said outer winding legs, and a casing of magnetic material enclosing said core and said windings, said core being formed from two abutting lamination stacks, the laminations in both stacks being identical to each other, and each lamination comprising an elongate strip having a longitudinal abutting edge provided with a plurality of slots therein to provide a plurality of parallel tongue portions which form said winding legs and said yoke portions.

5. A ballast as defined in claim 4 in which the end tongue portions are at least as long as any of the other tongue portions in order to provide a closed magnetic path at points adjacent said casing to prevent establishment of a fringing flux which affects said casing when a pair of like laminations are abutted.

6. A ballast as claimed in claim 5 in which the tongue portions adjacent to said end tongue portions are shorter than said end tongue portions in order to provide air gaps in said outer winding legs when a pair of like laminations are abutted.

7. A ballast for two fluorescent lamps comprising a core having a middle winding leg, two outer winding legs disposed parallel thereto, four yoke portions, two of which are disposed between adjacent winding legs, and two of which are disposed exteriorly of said outer winding legs, a transformer winding disposed on said middle winding leg, two reactor windings, each being disposed on one of said outer winding legs, and a casing of magnetic material enclosing said core and said windings, said core being formed from two abutting lamination stacks, the laminations in both stacks being identical to each other, and each lamination comprising an elongate strip having a longitudinal abutting edge provided with six slots therein to provide seven tongue portions, the second and sixth tongue portions constituting portions of said outer winding legs and being shorter than the remaining tongue portions in order to provide air gaps when a pair of like laminations are abutted, and the first and seventh tongues being at least as long as any of said remaining tongue portions to avoid presence of an air gap adjacent said casing in order to prevent establishing of a fringing flux which affects said casing when a pair of like laminations are abutted.

LEOPOLD MAUERER.
